MULTIOFFICE TELEPHONE SYSTEM

Filed April 30, 1930

UNITED STATES PATENT OFFICE

VICTOR S. THARP, OF ELMHURST, ILLINOIS, ASSIGNOR TO RESERVE HOLDING COMPANY, OF CHICAGO, ILLINOIS, A CORPORATION OF DELAWARE

MULTIOFFICE TELEPHONE SYSTEM

Application filed April 30, 1930. Serial No. 448,701.

This invention relates to improvements in multi-office telephone systems, particularly to improved trunking arrangements and apparatus for interconnecting the various offices of such systems.

Special service traffic such as toll recording, information, complaint, etc., are ordinarily handled at a central point in multi-office telephone systems. When the system comprises a number of automatic exchanges of relatively small size it is often impractical to provide a separate switchboard for each type of service and for this reason a switchboard for the combined special service traffic is provided. An alternative method is to route all special service traffic over the regular interoffice trunks to a manual exchange or toll switchboard. This latter arrangement is particularly desirable for small systems in which the volume of traffic is insufficient to warrant the services of a separate operator. There is, however, the disadvantage that important trunk lines are tied up and an additional load is imposed on the toll operator during the busy hours of the day.

One of the main objects of this invention is the provision of a special service trunking system which combines the advantageous features of both of the above methods without including their disadvantages. This end is attained by providing a switchboard of which the special service traffic of a group of small automatic exchanges is handled during the period of heavy traffic together with special trunking apparatus which routes this traffic to a manual office or toll board during the period of light traffic.

The various features of the invention which relate principally to new and improved apparatus for providing the above discussed type of service will be described in detail along with the operation of the various circuits involved.

A system disclosing the invention in one of its narrow aspects is shown in the accompanying single figure of drawing. This system comprises three offices designated, respectively, office A, office B and office C. Offices A and B are assumed to be of any well known type of automatic exchange. The

switching apparatus ordinarily provided for such exchanges is well known in the art and, since it forms no part of the invention, it has not been shown in detail. The two automatic exchanges are connected by trunk lines of which a representative trunk line T is shown. This particular trunk line is arranged for two-way service and terminates in a two-way repeater at office A and in trunk relay group ITR at office B. The three branches of the trunk at office B extend, respectively, to jack J at the special service switchboard, to the banks of finder switch F, and to the banks of local selectors in the exchange. At the switchboard, the busy visual signal S, call lamp L, and key K are associated with and individual to the jack J.

Office C is assumed to be a toll board or manual office which will be attended at all times. This office is connected by trunks, such as the trunk line T1, with office B at which it terminates in a repeater R. The trunk line may be of any well known type for example, such as the trunk lines disclosed in the United States Patent No. 1,571,966 to Ray. When such trunk lines are employed repeater R and trunk circuit R1 will correspond, respectively, to repeater R and the trunk circuit associated with trunk line X, of the above referred to patent.

The trunk line which is ordinarily provided with two branches extending, respectively, to an incoming selector or line switch and to the banks of selectors, is modified in this case by the provision of a third branch terminating in finder switch F. This additional branch is multiplied directly with the branch extending to the selector banks and does not necessitate any alterations in the repeater circuit. In the event that one-way trunks are employed in the system, the finder switch F is associated with an outgoing trunk in substantially the same manner as in the present disclosure.

The number of trunks equipped with finder switches will depend entirely upon the volume of traffic. A group of starting relays SR is provided for the finder switch group and

controls the operation of these switches by means of the usual chain circuit.

Special service trunks accessible to the local selectors in office B terminate in trunk relay groups, such as the group LTR, of which branches extend to the switchboard and to the banks of the finder switch F. The switchboard apparatus terminating these trunks has not been shown in detail since it corresponds in every respect to the apparatus terminating the trunk line T. Similar designations have been applied to corresponding conductors of the branches of both incoming and local trunks.

Trunk calls from office A will normally be extended to the operator at office B who will complete them in the usual way over an operator's switch train (not shown). However, when the switchboard at office B is to be left unattended the transfer key, such as key K, of each trunk line will be actuated, thereby placing the finder switches F in service. Under these conditions, calls over either the incoming or local trunks will cause a finder switch to connect with the calling trunk and extend the call over the trunk line T1 to the manual office or toll board at which it will be completed in the usual way.

The foregoing brief description sets forth the broad object of the invention. In order to better illustrate the various features of the invention the operations involved in setting up connections will now be described in detail.

The ordinary manner of handling calls from office A will be considered first. The calling subscriber dials the special service code and is connected with a trunk line, such as T, in the usual manner. A loop circuit is completed for the trunk at the outgoing repeater and line relay 11, which is bridged across conductors 1 and 2 of the trunk, operates. Ring-back-tone is applied to the trunk by way of the lower armature of relay 11, and ground, by way of the upper armature of this relay, is connected to signal conductor 5 which extends through normally-closed contacts of key K to lamp L. Lamp L lights to notify the operator of an incoming call. To answer the call the operator inserts the answering plug of a cord circuit (not shown) into jack J. Contacts 8 close and complete a circuit for the upper winding of relay 12 which operates, disconnects the incoming trunk conductors from the two windings of line relay 11 and extends them by way of the tip and ring contacts of the jack to the talking strands of the cord. Relay 11 restores and opens the circuits previously closed on its operation. The operator completes the call by inserting the calling end of the cord into a toll line or service trunk and then ringing or dialling in the well known manner.

When leaving the position unattended, the operator will actuate the transfer key K of

each trunk line terminating in the switchboard. All incoming calls over the trunk line T, under these conditions, will operate relay 11 as in the previous instance. The signal conductor 5, however, has been extended through the operated contacts of key K to relay 22 which operates under the control of relay 11. Relay 11 also removes ground from conductor 10, thereby marking the trunk line as calling in the banks of the finder switch. Relay 22 on operating completes a circuit through the normally-closed contacts of relay 31 to relay 33 which operates. Relay 33 at its upper armature completes a circuit for relay 32 and stepping magnet 38 in series, and at its lower armature connects test wiper 36 in parallel with relay 32. Non-calling trunk lines are marked in the banks of the finder by ground on the associated test contacts through back contacts of relays, such as relays 11 and 12. In case wiper 36 is standing on the contacts of a non-calling trunk the ground thereon will consequently shunt relay 32 and prevent it from operating. Magnet 38, however, will operate, step the wipers ahead to the next set of contacts and open its own circuit at the interrupter springs. This operation is repeated until the calling trunk is found which is marked by the absence of ground on the test contact. Relay 32 will no longer be shunted and will operate in series with magnet 38. The magnet, however, does not operate due to the high resistance of the relay. Relay 32 connects the talking conductors to repeater R at its outer armatures, disconnects relay 31 from the release trunk conductor at armature 39 and by means of that armature and armature 40 extends the release trunk conductor through to wiper 35 and completes a locking circuit for itself, closes a circuit for the lower winding of relay 31 at armature 41 and disconnects test wiper 36 at armature 42. Ground from the upper armature of relay 33 extends by way of armature 40 and wiper 35 through contacts of relay 11 to the lower winding of relay 12, and this relay operates to connect the talking conductors of the trunk through as in the previous instance. The calling loop is thereby extended over wipers 34 and 37 to the line relay of repeater R which operates. Repeater R then returns a holding ground on the release trunk in the usual way to maintain relay 32 of finder switch F and relay 12 of the trunk relay group operated. Relay 31 on operating disconnects relay 33 from the starting conductor and extends this conductor to the next switch of the train. Repeater R functions in the well known manner to extend the call over the trunk and operates a signal at the switchboard in which the trunk terminates.

At the end of the conversation the calling subscriber hangs up and opens the loop circuit, thereby releasing the line relay of the

repeater. Ground is removed from the release trunk and relays 32 of the finder switch and 12 of the trunk relay group restore to normal.

It will be noted that the starting conductor from relay group SR is shown extending through contacts of a relay of switch F, and as indicated by the dotted line through similar contacts of corresponding relays of other finder switches, to relay 21. The relay 31 which is normally connected to the release trunk conductor of the outgoing trunk operates whenever the associated trunk is busy. When all outgoing trunks are busy, an incoming call will operate starting relay 22 in the usual manner and this in turn will close a circuit for relay 21. Relay 21 on operating disconnects the ring-back-tone from conductor 9 and connects the busy tone thereto instead. This tone will be audible to the calling subscriber who is thereby informed that no trunks are available at this time. Should the subscriber maintain the connection until a trunk becomes idle, the finder associated with such trunk will immediately connect with the calling trunk and extend the call in the previously described manner.

Local calls to the special service operator are handled in substantially the same manner as trunk calls. The subscriber dials the code assigned to the operator and a local selector connects with an idle trunk such as the one terminating in trunk relay group LTR whereon line relay 51 operates over the calling subscriber's loop. Relay 51 grounds the signal conductor 5' which corresponds to conductor 5 of the incoming trunk and extends through contacts of a key, such as K, to a signal lamp, such as lamp L, associated with the local trunk. Relay 51 also connects a holding ground to the release trunk, removes ground from conductor 10' to mark the trunk as calling in the banks of the finder switches and prepares the switching circuit by closing a point in the circuit of relay 52. In case the switchboard is attended and key K is normal, the associated signal lamp will light, as in the previous instance. When the operator answers the call, ground from the jack contacts will be extended over conductor 7' to operate relay 53. Relay 53 on operating disconnects the ring-back-tone from the trunk at its lower armature and extends the talking conductors of the trunk through to the tip and ring contacts of the jack by way of conductors 3' and 4', removes ground from the starting lead, and connects an additional ground to the release trunk conductor. It will be noted in this case that the line relay is not disconnected when the operator answers, but continues to feed talking battery to the calling subscriber.

A call coming in over the local trunk with the special service switchboard unattended will be forwarded to the manual office in much

the same way as the previously described trunk calls. Ground on the signal conductor 5' instead of operating the associated call lamp at the switchboard will operate starting relay 22. Relay 22 will start an idle 70 finder switch to hunting as in previously described connections, the switch hunting for a trunk marked by the absence of ground on its test contacts, such as the one terminating conductor 10'. When the calling trunk is connected with, relay 52 operates over a circuit including contacts of relay 51, wiper 35 of the finder switch, armature 40 of the switching relay, and the upper armature of starting relay 33 of the finder switch. Relay 52 closes 75 a locking circuit for itself independent of the contacts of relay 51, connects a holding ground to the release trunk conductor, and disconnects the talking conductors of the trunk from line relay 51 and extends them 80 through without condensers to the wipers 34 and 37 of the finder switch. Finder switch F operates in exactly the same manner as was previously described and the repeater R returns the ground on the release trunk to hold 85 up switching relay 32 and relay 52 in the usual manner.

In the event of a call coming in on a local trunk when all finder switches are busy the calling subscriber will receive a busy tone in 90 the same manner as previously described for a trunk call. The release of the connection is accomplished in the same manner as the release of a trunk connection.

What is claimed is:

1. In a telephone system, an exchange, incoming trunk lines and outgoing trunk lines terminating in said exchange, a manual switchboard at the exchange for answering calls over said incoming trunk lines, and 100 switching mechanism at said exchange for automatically extending incoming trunk calls over said outgoing trunk lines when said switchboard is unattended.

2. In a telephone system, three exchanges, 110 trunk lines extending from the first exchange to a manual switchboard at the second exchange, other trunk lines extending from the second exchange to a manual switchboard at the third exchange, means in the first exchange for extending calls over said first trunk lines to the switchboard at the second exchange, and automatic means at the second exchange for further extending such calls over said other trunk lines to the switchboard 120 at the third exchange when the switchboard at the second exchange is unattended.

3. In a telephone system, three exchanges, 130 trunk lines extending from the first exchange to a manual switchboard at the second exchange, other trunk lines extending from the second exchange to a manual switchboard at the third exchange, finder switches terminating said other trunk lines at the second exchange and having access to said first trunk

line, and a key at said first switchboard for each of said first trunk lines for rendering said finder switches effective to connect with a calling one of said first trunk lines when the switchboard is unattended.

4. In a telephone system, incoming trunk lines terminating in a manual switchboard, outgoing trunk lines terminating in finder switches having access to said incoming trunk lines, a signal and a key at the switchboard for each incoming trunk line, a starting relay for controlling the operation of said finder switches, and means responsive to a call on one of said incoming trunk lines for operating either the associated signal or said relay depending on whether the associated key is normal or operated.

5. In a telephone system, an incoming trunk line terminating in a manual switchboard, an outgoing trunk line terminating in a finder switch having access to said incoming trunk line, a starting relay for said switch, a signal conductor grounded responsive to a call over said incoming trunk line, a signal normally connected to said conductor, and a key for disconnecting said conductor from said signal and for connecting it to said relay.

6. In a telephone system, incoming trunk lines terminating in a manual switchboard, outgoing trunk lines terminating in finder switches having access to said incoming trunk lines, a common starting relay for said switches, a signal conductor for each incoming trunk line adapted to be grounded responsive to a call over the associated trunk line, a signal normally connected to each conductor, and a key for each incoming trunk line for disconnecting the associated conductor from its corresponding signal and for connecting it to said common relay.

7. In a telephone system comprising three serially related exchanges, interconnecting trunk lines, manual switchboards in the second and third exchanges, a signal at the switchboard in the second exchange adapted to operate in response to a call over a trunk line from the first exchange, switching mechanism in the second exchange adapted to automatically extend incoming trunk calls from the first exchange to the switchboard in the third exchange, and a key at the switchboard in the second exchange for rendering either said signal or said switching mechanism effective.

8. In a telephone system, a tandem exchange, incoming and outgoing trunk lines terminating in said exchange, finder switches associated with said outgoing trunk lines, means responsive to a call over an incoming trunk line for operating the switch associated with an idle outgoing trunk line to connect the same to the calling trunk line, and means responsive to a call over an incoming trunk line for applying a busy tone there-

to providing no idle outgoing trunk line is available.

9. In a telephone system, incoming trunk lines terminating in a manual switchboard, outgoing trunk lines terminating in finder switches having access to said incoming trunk lines, a signal at the switchboard for each incoming trunk line, a starting relay for causing the finder switch associated with an idle outgoing trunk line to operate and connect with a calling incoming trunk line, a key at the switchboard for each incoming trunk line for rendering either the associated signal or said relay effective, and means controlled by said relay for applying a busy tone to a calling incoming trunk line when all outgoing trunk lines are busy.

10. In a telephone system comprising three serially related exchanges interconnected by trunk lines, manual switchboards in the second and third exchanges, a signal at the switchboard in the second exchange operated responsive to an incoming call from the first exchange, automatic switches in the second exchange operated responsive to an incoming call from the first exchange to extend such call to the switchboard in the third exchange when the switchboard in the second exchange is unattended, and means at the second exchange operated responsive to an incoming call from the first exchange for returning a busy tone to the calling subscriber when the switchboard in the second exchange is unattended and all trunks between the second and third exchanges are busy.

11. In a telephone system, a trunk line accessible at one end to automatic switches and having two normally disconnected branches at the other end, a manual switchboard terminating one of said branches, finder switches having access to the other of said branches, a line relay bridged across the talking conductors of the trunk line operative responsive to the extension of a call to the trunk line for either signalling the operator at said switchboard or for initiating the operation of one of said finder switches, means responsive provided the call is answered from the switchboard for connecting the trunk line to said first branch, and means responsive provided one of said finder switches connects with said other branch for disconnecting the trunk line from said line relay and for connecting it to said other branch.

In witness whereof, I hereunto subscribe my name this 28th day of April, A. D. 1930.

VICTOR S. THARP.
